UNITED STATES PATENT OFFICE.

FREDRICK C. MILLER, OF NEWPORT, KENTUCKY.

DESIGN FOR A COUPLING-REACH FOR ROLLER-SKATES.

SPECIFICATION forming part of Design No. 16,130, dated June 16, 1885.

Application filed May 1, 1885. Term of patent 14 years.

To all whom it may concern:

Be it known that I, FREDRICK C. MILLER, a citizen of the United States, residing at Newport, in the county of Campbell and State of Kentucky, have invented a new and original Design for a Combined Coupling-Reach and Foot-Plate for Roller-Skates, of which the following is a specification, reference being had to the accompanying drawings, forming a part thereof.

Figure I is a side elevation, and Fig. II a plan, of my novel design for a combined coupling-reach and foot-plate for roller-skates. Fig. III is a transverse sectional view of the coupling-reach on the line III III, Figs. I and II.

The principal novel features of my design are the shape and configuration of the foot-plate and coupling-reach, as shown in the drawings. These parts consist of an arched

or curved bar, 1, of $\cap$ shape in cross-section, having openings 5 in the sides 3 at the ends thereof, presenting projections 6 and 7. 2 2° are foot-plates surmounting the bar, and 4 depressions through the plates into the ends 25 of the bar.

Having thus described my design, the following is what I claim as new therein and desire to secure by Letters Patent:

The design for a coupling-reach for roller-skates herein shown and described, the same consisting of an arched or curved bar of $\cap$ shape in cross-section, having openings at the ends thereof, a flat top surmounting one end thereof, and an upwardly-inclined top 30 surmounting the other end thereof. 35

FREDRICK C. MILLER.
